UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

FEEDING DEVICE FOR ROCK DRILLS

Application filed October 19, 1928. Serial No. 313,528.

This invention relates to rock drills of the fluid actuated type, but more particularly to a feeding device which forms a support for the rock drill and is intended to advance the 5 drilling mechanism towards the work in accordance with the penetration of the working implement into the material being drilled.

One object of the invention is to prevent the rebound of the drilling mechanism from 10 the work due to the reciprocatory action of the hammer piston of the drill.

Another object is to enable the feeding device to be readily controlled, both for applying the pressure to the drilling mechanism 15 and to retract such drilling mechanism from the work.

Other objects will be in part obvious and in part pointed out hereinafter.

In the drawings illustrating a practical 20 embodiment of the invention, and in which similar reference characters refer to similar parts,

Figure 1 is a side elevation of a rock drill equipped with a feeding device in accordance 25 with the practice of the invention, and

Figure 2 is a sectional elevation of the feeding device taken through Figure 1 on the line 2-2 looking in the direction indicated by the arrows.

Referring more particularly to the drawings, A generally designates a rock drill of the stoper type having a percussive element B which comprises a cylinder C and a front head D. The front head D serves as a guide 30 for a drill steel E and is secured to the cylinder C by means of spring pressed side bolts F.

Connected to the rearward end of the cylinder C is a head block G to which is attached in this instance a handle H having a grip portion J adapted to be grasped by the operator for oscillating the drill during its operation and thus constantly changing the position of the drill steel E in the hole being drilled.

The pressure medium, such as compressed air or steam, may be conveyed to the rock drill through a connection K leading from a source of pressure fluid supply. The connection K is connected to the head block G adjacent the throttle valve, only the handle

L of which is shown, and whereby the admission of pressure fluid into the drill may be controlled.

In accordance with the practice of the invention means are provided for constantly advancing the rock drill in accordance with the penetration of the drill steel E into the material being drilled so that the portion of the drill steel against which the blows are being delivered will be constantly within the range of travel of the hammer piston (not shown) but for which the cylinder C forms a housing. These means in the present instance comprise a piston O which extends slidably into a feeding cylinder P. The piston O has a head Q which is seated on the head block G and is secured thereto by means of bolts R which may also serve to secure the head block G to the cylinder C.

The lowermost or free end of the piston O is in the form of a head S having a series of grooves T for the accommodation of sealing means, such as piston rings U to prevent leakage of the pressure medium between the head S of the piston and the cylinder P. The head S of the piston may be of any suitable length to assure accurate alignment between the piston and the cylinder. The stem or rod V of the piston O is of course of smaller diameter than the head S thus forming a shoulder W which may abut an internal flange or shoulder X in the upper end of the cylinder P to prevent separation of the piston and the cylinder.

The flange X is preferably located a slight distance from the end of the cylinder P so that it may act as a seat for a wearing ring Y disposed in a recess Z in the end of the cylinder P. The wearing ring Y may be conveniently secured in the recess Z by means of an internally threaded collar c threaded on the end of the cylinder P and having a lateral flange d to bear against the end of the ring Y.

In drills of the type to which the present invention pertains it is the practice to introduce a pressure fluid such as compressed air or steam into the feeding cylinder to act against the piston O for constantly maintaining the percussive element within striking range of the drill steel E.

While this mode of feeding the drill to the work has to some extent proved satisfactory, it has however, been found that the highest drilling efficiency of the drill cannot be obtained through the use of such compressible fluid. This is due to the fact that when the hammer piston rebounds in the cylinder C of the drill the rebound is transmitted to the fluid in the feeding cylinder with the result that there is caused a certain degree of relative longitudinal movement between the drilling mechanism and the working implement. This is highly objectionable since when the hammer piston strikes against the drill steel a considerable amount of the force of the blow of the hammer piston is utilized for carrying the drill steel into contact with the material being drilled. Whereas, the ideal condition is to maintain the cutting end of the drill steel in substantially constant contact with the rock.

In order therefore to insure against such undesirable retraction of the drilling mechanism from the rock, means are provided for introducing an incompressible fluid, such as water e into the feeding cylinder P to advance the piston O and thus also the rock drill A. To this end the feeding cylinder P is provided with a reservoir f for water e. The reservoir f may, as illustrated, encircle the cylinder O and is provided with a head g which seals one end of the reservoir f and has an annular flange h which extends into the end of the reservoir f and serves to centralize said reservoir with respect to the cylinder P.

A closure is provided for the opposite end of the reservoir f, and in this instance also for the corresponding end of the feeding cylinder P, by a head j having an annular groove k in its end and into which extend the ends of the cylinder P and the reservoir f. The head j also acts as a foot piece to which may be secured the pointer o which engages an element such as the floor of a mine, or, as shown a plank p, to support the drill and also to assure against misalignment of the drilling mechanism with respect to the hole being drilled.

The head j in this instance is provided with a valve chamber q for the reception of a throttle valve r having a stem s which extends to the exterior of the head j and to which is secured a throttle handle t. The throttle handle t preferably is of the multi-lever type so that it may be engaged at either side of the stem s for manipulating the throttle valve r. The wings u of the handle t are preferably of such length that they may be readily engaged by the foot of the operator for actuating the throttle valve. Lugs v which may form an integral part of the head j act as stops for the wings u of the throttle handle.

The throttle valve r is preferably of less length than the chamber q wherein it is disposed and has a central chamber w which is

in constant communication with the reservoir f through a passage x in the head j. In addition to the central chamber w the throttle valve is also provided with a pair of ports y and z. The port y acts as an inlet port and is adapted to register with an inlet passage 2 leading from the valve chamber q to the cylinder P, and the port z serves as an exhaust port which in one limiting position of the throttle valve r registers with an exhaust passage 3 in the head j and through which the liquid or water e may flow from the cylinder P into the throttle valve and thence into the reservoir as will be presently described.

The parts y and z are of course so located that only one of them may be positioned to place the chamber w of the throttle valve into communication with the cylinder P at one time. In this way when liquid is being introduced into the cylinder there can be no introduction of liquid from the cylinder. Similarly while liquid is being exhausted from the cylinder P the inlet port y will occupy a position wherein it will be out of registry with the inlet passage 2.

In order to insure against the forcing of liquid from the cylinder P during the time that it is desired to exert a constant and incompressible pressure against the feeding piston O, the inlet passage 2 is provided with a check valve in the form of a ball 4 seated on a valve seat 5 in the passage 2 to form a seal at this point. Preferably a spring 6 is also disposed in the passage 2 to constantly tend to press the ball 4 to its seat, and a seat 7 threaded into the end of the passage 2 serves as a seat for one end of the spring and has a port 8 through which liquid may flow into the feeding cylinder P.

The reservoir f may be of a volume capable of accommodating a supply of liquid or water e somewhat in excess of the volume of the feeding cylinder P so that the piston O may be entirely extended in the cylinder P by the liquid without causing the introduction of a portion of the pressure fluid into the feeding cylinder P.

The pressure fluid utilized for thus transferring the water from the reservoir into the cylinder P may be obtained from the same source as that utilized for actuating the rock drill and in order to introduce such pressure medium into the reservoir f the said reservoir is provided with a control valve 9 connected in this instance to the head g. The control valve 9 is preferably of the two-way type and comprises a casing 10 to which is connected a conduit 11 for conveying pressure fluid to the reservoir. In the casing 10 is a plug valve 12 having a recess 13 adapted to register with the connection 11 and a connection 14 leading to the reservoir for admitting pressure fluid into the reservoir and also to establish communication between the connection 14 and an exhaust port 15 in the casing 10 for exhaust-

ing pressure fluid from the reservoir *f* to the atmosphere. The plug valve is preferably of the rotatable type and is accordingly provided with a lever 16 whereby it may be manipulated.

The operation of the device is as follows: After the drilling mechanism has been placed in substantially the correct drilling position the valve 12 may be opened to establish communication between the conduit 11 and the connection 14 and pressure fluid will then flow through these channels into the reservoir *f* to create a pressure on the water *e*.

After rocking the throttle valve *r* into a position in which the inlet port *y* registers with the inlet passage 2 the water *e* or its equivalent will flow from the chamber *w* in the throttle valve through the port *y* and the inlet passage 2, past the ball 4 and into the cylinder *P* to act against the piston *O* for forcing the drill steel *E* against the material intended to be drilled. The water *e* will exert an adequate pressure against the piston *O* to hold the drill steel firmly against the work and maintain the entire drilling mechanism in a position to insure the most efficient drilling. The percussive element may then be set in operation and as the drill steel penetrates the rock, water will be constantly forced into the cylinder *P* to actuate the piston *O* and the drill toward the work. The water is entrapped in the feeding cylinder *P* by the check valve or ball 4 in the inlet passage 2 and owing to its incompressible nature will form a substantially rigid abutment for the piston *O*. The drilling mechanism will therefore be held against retrograde movement during its operation and its correct position with respect to the drill steel will be assured.

Whenever it is desired to retract the drilling mechanism, the valve 12 may be rocked to establish communication between the connection 14 and the exhaust port 15 in the casing 10 for exhausting the pressure fluid from the reservoir *f* and at the same time to cut off communication between the conduit 11 and the reservoir. Thereafter the throttle valve *r* may be manipulated to carry the port *z* into registry with the exhaust passage 3. The water will then be forced from the cylinder *P* by the pressure of the weight of the drill and will be returned through the throttle valve and its chamber and through the passage *w* to the reservoir *f* wherein it may remain until required for a succeeding drilling operation.

From the foregoing description the advantages of this invention will be readily apparent to those skilled in the art to which it appertains and I wish it to be understood that while I have shown only one specific embodiment thereof the invention is susceptible of further modification without departing from its spirit or from the scope of the claims.

I claim:

1. A feeding device for rock drills, comprising a pair of relatively movable members, one of which is adapted to be connected to the rock drill, a reservoir for liquid, means for introducing a pressure medium into the reservoir to force liquid therefrom into one of the members to actuate the other member and the rock drill in the direction of the material intended to be drilled, means interposed between the reservoir and said members for automatically controlling the flow of liquid from the reservoir into the member, and a manually operable valve for controlling the flow of liquid from the member to the reservoir and from the reservoir to said means.

2. A feeding device for rock drills, comprising a feeding cylinder, a piston in the feeding cylinder and connected to the rock drill, a reservoir on the cylinder for liquid, passages in the cylinder affording communication between the reservoir and the cylinder, means in one of the passages for automatically controlling the flow of liquid from the reservoir into the cylinder, manually operable means for selectively controlling the flow of liquid through another passage from the cylinder into the reservoir, and means for introducing a pressure medium into the reservoir to force liquid therefrom into the cylinder for actuating the piston and the rock drill in the direction of the material intended to be drilled.

3. A feeding device for rock drills, comprising a feeding cylinder, a piston in the feeding cylinder and connected to the drill, a reservoir for liquid encircling the cylinder, passages affording communication between the reservoir and the cylinder, a check valve in one passage automatically controlling communication between the reservoir and the cylinder, a throttle valve controlling the flow of liquid from the cylinder to the reservoir, and a valve for introducing a pressure medium into the reservoir to force liquid therefrom into the cylinder to actuate the piston and the drill in the direction of the material intended to be drilled and for exhausting such pressure medium from the reservoir preparatory to the withdrawal of the drill from the work.

4. A feeding device for rock drills, comprising a feeding cylinder, a piston in the feeding cylinder and connected to the drill, a reservoir for liquid encircling the cylinder, a head forming a closure for the cylinder and the reservoir and having a valve chamber, a passage in the head affording communication between the reservoir and the valve chamber, inlet and exhaust passages in the head leading from the valve chamber to the reservoir, a check valve controlling the inlet passage, a throttle valve in the valve chamber controlling the exhaust passage, and a valve for introducing a pressure medium into the reservoir to force liquid therefrom into the cylinder.

inder to actuate the piston and the drill in the direction of the material intended to be drilled and for exhausting such pressure medium from the reservoir preparatory to the withdrawal of the drill from the work.

In testimony whereof I have signed this specification.
